CLAIM

The ornamental design for hand controller buttons, as shown and described.

DESCRIPTION

FIG. 1 is a top, right-side, front perspective view of hand controller buttons showing my new design;

FIG. 2 is a back elevation view thereof;

FIG. 3 is a front elevation view thereof;

FIG. 4 is left-side elevation view thereof

FIG. 5 is a right-side elevation view thereof;

FIG. 6 is a top plan view thereof; and,

FIG. 7 is a bottom plan view thereof.

The dash-dash broken lines illustrate portions of the hand controller buttons that form no part of the claimed design.
